UNITED STATES PATENT OFFICE.

RAYMOND HUFFORD, OF NEW YORK, N. Y., ASSIGNOR, BY MESNE ASSIGNMENTS, TO HANDY GOVERNOR CORPORATION, OF DETROIT, MICHIGAN, A CORPORATION OF MICHIGAN.

AUTOMATIC GOVERNOR FOR INTERNAL-COMBUSTION ENGINES.

Application filed September 1, 1926. Serial No. 133,039.

This invention relates to automatic governors for internal combustion engines and more particularly to means for automatically rendering the governor inoperative under certain conditions of use.

Automatic governors, particularly of the type referred to in co-pending application filed by me and Herman G. Adler under even date herewith, Serial No. 133,040, depend for their operation upon the differential pressure occurring in the intake pipe line of the engine and the atmosphere. Under certain operating conditions when it becomes necessary to shift into low or intermediate gears, it may become desirable to discontinue the functioning of the governor. Therefore, to meet that condition it is proposed to equip the governor with an attachment operated by any suitable part of the gear shifting mechanism and automatically cut off communication with the atmosphere so that the governor will be inoperative when the vehicle operates in a gear or gears other than high gear.

Accordingly, the present invention has primarily in view a novel, practical and reliable device for automatically rendering the governor inoperative excepting when the vehicle is moving under normal conditions under load, and in high gear.

While various expedients may be resorted to to accomplish this object a practical embodiment of the invention is shown in the accompanying drawings, in which:

Figure 1 is a view illustrating more or less diagrammatically the arrangement employed and showing the attachment in detail as applied to a Ford car.

Figure 2 is a top plan view of a portion of the attachment shown in Figure 1, partly in section to show the construction involved.

Similar reference characters designate corresponding parts throughout the several figures of the drawings.

In the embodiment shown the automatic governor device which is interposed in the intake pipe line of the engine is designated generally as A. The construction of this device is immaterial but for purposes of illustration it may be pointed out that a governor of the type shown in co-pending application filed by me and Herman G. Adler, previously referred to, has been diagrammatically shown in Figure 1. This type of governor has a ported cover B which ordinarily communi-

cates with the atmosphere so that when a vacuum exists in the intake line the atmospheric pressure will actuate the piston-plunger A to automatically throttle the intake line in accordance with the load and speed of the engine.

The present invention proposes to cover and seal the atmospheric intake end of the governor with a hood or cover 1, the same having attached thereto in an air-tight manner a tube or pipe 2 which communicates at its other end with an automatic valve device designated generally as C and forming a part of the attachment constituting the present invention.

As will be observed from Figures 1 and 2 the said attachment preferably includes in its organization a bracket 3 which may be connected as indicated at 4 to a suitable frame part 5 of the vehicle chassis. One end of the bracket 3 is preferably enlarged as at 6 to provide a hollow valve casing having a port 7 communicating with the atmosphere. The chamber provided by the hollow casing 6 is adapted to receive a sliding valve member or cut-off 8 which is normally thrust outwardly by a spring 9 confined between the bottom of the chamber and the bottom of the valve 8. The said valve is provided with a stem 10 slidably guided in a cover or plug 11 through which it is adapted to project so that it may be engaged by a part of the gear shifting mechanism designated generally as S. In the embodiment shown the type of gear shift includes a member which is adapted to shift horizontally when moved by the operator of the vehicle thereby to permit the valve 8 to be moved by the pressure of the spring 9 to close the port 7.

The normal position of the gear shifting means 8 is shown in dotted lines in Fig. 1. In that position the stem 10 of the valve is pressed inwardly to compress the spring and cause the body of the valve 8 to move out of obstructing relation to the port 7. It will therefore be apparent that normally the hood 1 is in communication with the atmosphere through the pipe line 2 since the chamber within the casing 6 is also open to the atmosphere. However, when the gear shifting means S is moved to the full line position shown in Fig. 1, the spring 9 will move the valve 8 so that the port 7 will be closed. The chamber of the hood 1 will therefore be cut

off from the atmosphere and the piston-plunger of the governor device A can not operate.

When using a low or intermediate gear of a transmission, it is necessary for the engine to speed up and consequently the vacuum in the intake line is relatively great. Under that tendency the governor device would function to such a degree as to possibly hamper the motor in overcoming the inertia of moving the load. However, with the present attachment the governor is rendered inoperative when the vehicle is in low or intermediate gear so that no difficulty in starting the vehicle is experienced. When the vehicle is under way and moving in high gear, the automatic governor device will function in its normal way.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:—

1. In an automatic suction responsive type governor device for internal combustion engines, the combination with the governing device normally open to the atmosphere and adapted to be moved by the difference of pressure between the vacuum in the intake pipe line and the atmosphere and a gear shifting part, of means actuated by said gear shifting part for cutting off atmospheric pressure from said automatic governing device to render the same inoperative.
2. In an automatic suction responsive type governor device for internal combustion engines, the combination with the governing device normally open to the atmosphere and adapted to be moved by the difference of pressure between the vacuum in the intake pipe line and the atmosphere and a gear shifting part, of valve means actuated by the movement of said gear shifting part for cutting off communication between the atmosphere and the governing device.
3. An attachment for automatic suction responsive type engine governors having an at-

mosphere port normally open to the atmosphere when the engine is operating, of automatic means for closing said atmosphere port 55 to render the governing device inoperative under certain predetermined conditions.

4. An attachment for automatic suction responsive type engine governors having an atmosphere port normally open to the atmosphere when the engine is operating, of means for closing said atmosphere port to render the governing device inoperative, said means being actuated by a gear shifting part 60 of the vehicle.

5. An attachment for automatic suction responsive type engine governors having an atmosphere port normally open to the atmosphere when the engine is operating, of means for closing said atmosphere port to 70 render the governing device inoperative, said means comprising a hood, a conduit connected to the hood, a valve member having an atmosphere port connected with said conduit, and means for operating said valve member.

6. An attachment for use in connection with internal combustion engine governors of the suction responsive type which control the speed of the engine by regulating the supply of mixture and are normally open to the 80 atmosphere, comprising in combination with the governor, a hood adapted to be fitted to the air intake side of the governor, a conduit connected to said hood, a bracket, a valve device carried by the bracket and including an 85 atmosphere port and a spring pressed plunger having a stem, and means for engaging said stem to actuate the plunger.

7. An attachment for use in connection with internal combustion engine governors 90 of the suction responsive type which control the speed of the engine by regulating the supply of mixture and are normally open to the atmosphere, comprising in combination with the governor, a hood adapted to be fitted to the air intake side of the governor, conduit connected to said hood, a bracket, a valve device carried by the bracket and including an atmosphere port and a spring pressed plunger having a stem, and a gear shifting member 100 for engaging the stem of the plunger.

In testimony whereof I hereunto affix my signature.

RAYMOND HUFFORD.
